UNITED STATES PATENT OFFICE.

JAMES D. WILLIAMSON, OF READING, PENNSYLVANIA, ASSIGNOR OF ONE-HALF TO
CHARLES A. MILLS, OF WYOMISSING, PENNSYLVANIA.

RIB-JOINT DEVICE FOR UMBRELLAS.

1,145,285.

Specification of Letters Patent.

Patented July 6, 1915.

Application filed May 28, 1914. Serial No. 841,687.

To all whom it may concern:

Be it known that I, JAMES D. WILLIAMSON, a citizen of the United States, residing at Reading, in the county of Berks and State of Pennsylvania, have invented certain new and useful Improvements in Rib-Joint Devices for Umbrellas, of which the following is a specification.

My invention relates to rib-joint devices for umbrellas and parasols, its main features applying to both the upper notch and runner; and more particularly to constructions employing ordinary ribs and braces provided with pivot-eye ends.

My main object is to provide for independently removing and replacing such ribs or braces, and to this end the invention consists essentially in employing independently-removable pivot-wires for the several ribs or braces, as fully described in connection with the accompanying drawings; the novel features of the invention being specifically pointed out in the subjoined claims.

Figure 1 is a sectional view of an upper notch device embodying my invention in preferred form; and Fig. 2 is a similar view illustrating its application to the lower runner. Fig. 3 is an elevation taken at right angles to Fig. 1; Fig. 4 is a bottom-plan view of the main notch part; and Figs. 5 and 6 are perspective views of the retaining ring parts thereof. Fig. 7 is a plan view of the main runner part; and Fig. 8 is a perspective view of one or other of the two retaining rings employed therewith; and Fig. 9 is a separate view of one of the pivot wires.

The umbrella stick 2 may be of ordinary construction, excepting that a special spring 40 catch 3 is provided as shown, in connection with the upper notch, for a purpose herein-after stated.

The main notch ring 5 is formed with a series of radial rib-receiving slots 6, 6, 6, corresponding with the number of ribs employed, as usual. The partition wings 7, 7, 7, which form the side walls of these slots, are circularly grooved on their lower faces so as to form circumferential pivot-wire recesses 8, 8, 8; and each is also provided with a second recess 9, arranged at approximately right angles to 8 as indicated and extending longitudinally, or parallel with the axis, of the ring. These recesses 8 and 9 are adapted to receive the respective end portions of

an angular rib-pivot wire 10, when the latter is engaged in the eye 11 of a rib 12 and the latter is entered in one of the rib-receiving slots 6; there being a separate rib-pivot wire 10 for each rib, and each wire being adapted to seat at its opposite ends respectively, in a circumferential recess 8 of one partition and a longitudinal recess 9 of an adjacent partition. To provide for properly retaining these rib-pivot wires 10, and the ribs 12 suspended therefrom, in described engagement with the notch ring 5, I employ, as shown, two co-operating retaining rings, 15 and 16. These rings are provided with radial slots, 17 and 18 respectively, corresponding with the rib-receiving slots 6 of the notch ring 5, so as to permit of its ribs swinging freely to their closed vertical positions; but one of the partition wings between two slots of the ring 15, is removed, so as to form a widened slot 20 which serves as an aperture through which a single rib and its pivot wire may be withdrawn, while a corresponding partition-lug or projection 21 is formed on the co-operating ring 16 to normally take the place of the removed partition of the ring 15.

The normal positions of the upper notch parts are indicated in Figs. 1 and 3. Each rib with its pivot wire, being secured in jointed engagement with the main notch ring 5 by the retaining rings 15 and 16. As shown the ring 16 is formed with a sleeve portion 16^b, which engages the special spring catch 3 so as to be firmly carried by the latter, and held against rotation on the stick; and the ring 15 is rotatively fixed to 16 by an engaging pin 30, so that the rib-receiving slots of the several parts are in fixed alinement to permit free swing of the pivoted ribs. The ring 15 is preferably held against end-wise movement on the stick, by means of a slightly projecting pin 31 as indicated, but the sleeve ring 16 may be moved when desired, by depressing the spring catch 3 so as to permit of its passing over the latter.

In case it becomes necessary to remove a particular rib, the spring catch 3 is thus depressed and the sleeve ring 16 is turned with the ring 15 to bring the pivot-wire aperture 20 of the latter into register with such rib; after which a slight end wise movement of the ring 16 along the stick will give room for withdrawing said particular rib and its

pivot wire from the notch. After replacing this rib and pivot wire, the operation may be repeated as desired, and the parts finally returned to normal position without in any 5 way affecting the other ribs which are constantly held in the notch by the ring 15. The application of my invention to the lower runner involves only slight structural modifications, as indicated in Figs. 2, 7, 10 and 8. The rib-receiving slots, 6^a, 6^a, 6^a, of the runner joint ring 5^a are open at the top to permit free swing of the stretchers 12^a, and no corresponding slots such as are shown in the upper notch construction, are 15 required in the coöperating retaining rings 15^a, 16^a. Also these latter rings may be mere duplicates, as shown, each having a pivot-wire aperture 33, 34 which must be set into register with the pivot-eye end of a stretcher 20 in order to enable the latter to be withdrawn from the runner. It will be understood that the runner joint ring 5^a is fixed to the runner sleeve 32, while the retaining rings 15^a, 16^a are rotatably mounted thereon, and that the operation is essentially the 25 same as in the case of the upper notch described; also that the detail constructions which have been specifically described may be readily modified without departing from 30 the spirit of the invention.

What I claim is:

1. A rib-joint device for umbrellas comprising a stick ring having regularly spaced 35 rib-slots and partitions provided with pivot-wire recesses, ribs in said slots having pivot-wire apertures, a separate pivot-wire for each rib loosely inserted through the rib-aperture and engageable in said recesses on opposite sides of a rib-slot, and adjustable 40 means for jointly locking or independently releasing said pivot wires.

2. A rib-joint device for umbrellas comprising a stick ring formed with a series of

rib-receiving notches and with partitions having series of pivot-wire recesses extending respectively circumferentially and longitudinally of the ring, a series of angular rib-pivot wires the ends of each of which are engageable respectively in a circumferential and a longitudinal recess, and adjustable means for jointly locking or independently releasing said pivot wires. 45

3. A rib-joint device for umbrellas comprising a stick ring having regularly spaced 55 rib-slots and partitions provided with pivot-wire recesses, ribs in said slots having pivot-wire apertures, a separate pivot-wire for each rib loosely inserted through the rib-aperture and engageable in said recesses on opposite sides of a rib-slot, an adjustable 60 retaining ring having a pivot-wire aperture, and an adjustable aperture covering. 65

4. A rib-joint device for umbrellas comprising a stick ring having regularly spaced 70 rib-slots and partitions provided with pivot-wire recesses, ribs in said slots having pivot-wire apertures, a separate pivot-wire for each rib loosely inserted through the rib-aperture and engageable in said recesses on opposite sides of a rib-slot, an adjustable retaining ring having a pivot-wire aperture, and an adjustable aperture covering ring. 75

5. A rib-joint device for umbrellas comprising a notch ring having regularly spaced 80 rib-slots, and partitions provided with pivot-wire recesses; a correspondingly slotted retaining ring having one partition removed to provide a pivot-wire aperture, and a relatively movable coöperating retaining ring having a partition projection. 85

In testimony whereof I affix my signature in presence of two witnesses.

JAMES D. WILLIAMSON.
